SERVICE VALVE LINE CLAMP

John W. Mullins, P.O. Box 20524,
Oklahoma City, Okla. 73120

Filed Aug. 22, 1969, Ser. No. 18,820

Term of patent 14 years

Int. Cl. D23—01

U.S. Cl. D23—19

FIG. 1

FIG. 4

FIG. 2

FIG. 5

FIG. 3

FIG. 6

FIG. 1 is a perspective view of a service valve line clamp showing my new design, the line and service valve being shown in broken lines for illustrative purposes only.

FIG. 2 is a top view of FIG. 1.

FIG. 3 is a bottom view of FIG. 1.

FIG. 4 is a side elevational view.

FIG. 5 is a right end view of FIG. 4.

FIG. 6 is a left end view of FIG. 4.

I claim:

The ornamental design for a service valve line clamp, substantially as shown and described.
